United States Patent Office.

JOHN J. MYERS, OF BALTIMORE, MARYLAND, ASSIGNOR TO BENTLEY C. BIBB, OF SAME PLACE.

Letters Patent No. 97,956, dated December 14, 1869.

FIRE-PLACE FUEL-MAGAZINE STOVE.

The Schedule referred to in these Letters Patent and making part of the same.

To all whom it may concern:

Be it known that I, JOHN J. MYERS, of the city of Baltimore, in the State of Maryland, have invented certain new and useful Improvements on Fire-Place Fuel-Magazine Stoves; and I do hereby declare that the following is a full, clear, and exact description thereof, reference being had to the accompanying drawings, making part of this specification, in which—

Figure 1, plate 1, is a front elevation of the improved stove.

Figure 2, plate 1, is a top view of the stove, with the rear portion of the top broken away.

Figure 3, plate 2, is a vertical section, taken centrally through the stove from side to side.

Figure 4, plate 2, is a vertical section, taken centrally through the stove from front to rear.

Figure 5, plate 2, is a section taken in the horizontal plane indicated by dotted lines $x x$, in figs. 3 and 4.

Figures 6 and 7, plate 2, are different views, showing the manner of connecting together the screen-section and inside cover, and of applying the same to the top-feed magazine.

Similar letters of reference indicate corresponding parts in the several figures.

This invention relates to certain novel improvements on that class of magazine-stoves which is adapted for being arranged in fire-places, so as to partly project therefrom. Such stoves require to be very short, in order to be received in fire-places as at present constructed; and for the purpose of giving the greatest possible vertical capacity to the magazines, the latter have been carried nearly to the top of the upper sections of the stoves, and feed-openings provided through the tops of said sections and magazines, for allowing the latter to be filled with fuel.

The nature of my invention consists—
First, in the gas-escape passage of the feed-chute for a magazine fire-place stove.

Second, it consists in the curved door for closing the gas-escape passage of the chute and the feed-passages through the top of the stove and magazine.

Third, it consists in attaching this curved door to the stove, in such a manner that it forms a permanent part of the stove, and yet is movable, so as to open the feed-openings of the stove and magazine, and also the gas-passage of the chute. It also consists in arranging said door to open and close by a movement in the path of a vertical circle.

Fourth, it consists in the combination of ornamental air-distributing screens, either stationary or movable, with a curved door, which is a permanent part of the stove, but movable, so as to open and close the gas-passage and the feed-opening of the stove and magazine.

Fifth, it consists in attaching the screen, or a sec-

tion thereof, to the curved door, so as to be easily disconnected from the same when desirable.

Sixth, it consists in the combination of a series of short air-heating pipes, the combustion-chamber communicating at the back with said pipes, the hollow base, the return-columns, and the damper serving to make a direct or indirect draught.

Seventh, it consists in the combination of the damper, which produces the direct or indirect draught, the chute, with gas-escape passage through it, the flue or extension-chamber, with gas-escape in it, of the upper section of the stove, and the main draught-flue, whereby a direct escape for gas into the draught-flue from the chute, when the feed-door is opened, is at all times maintained, whether the damper is adjusted for a direct or indirect draught.

Eighth, it consists in the flue-extension of the upper section of the stove, furnished with a gas-escape and with a damper, in combination with the lower combustion-chamber, which is furnished with downward flues, into which the products of combustion first pass when the damper is closed.

To enable others skilled in the art to understand my invention, I will describe its construction and operation.

In the accompanying drawings—

A represents the hollow base-section of the fire-place stove, which has its ash-chamber *b* separated from the space *c*, by means of a semicircular division-plate.

The space *c* communicates with the space enclosed by top section *C*, by means of the vertical side columns *E E*, and short horizontal pipes *a a*, as shown in figs. 1 and 3.

B is the section which encloses the combustion-chamber, and which is provided with mica-light windows or doors, or both windows and doors. This combustion-chamber contains the fire-pot or fire-brick lining, and has a grate at its base.

The upper back portion of the combustion chamber is extended horizontally backward, as shown at *B'*, figs. 4 and 5, for the purpose of conducting the products of combustion into the upper end of a number of descending flue-pipes, *S*, which lead from said back extension *B'* down, and empty into the flue-space *e*, in the base *A* of the stove. These pipes *S* are small in diameter, and are isolated from the combustion-chamber section and from each other, so that air can circulate freely about them. They afford a large amount of heat-radiating surface, for heating air flowing into the space at the back of the stove.

The combustion-chamber section *B B'* is capped by a horizontal plate, on which is supported the top section *C*.

This section encloses a chamber, which is separated

below from the combustion-chamber, as shown in figs. 3 and 4, but which is in communication with this chamber, through the medium of the passages B', S, c', E, and a.

From the inner margin of the diaphragm, separating chambers B C, the lower section F of the fuel-magazine is suspended, and upon this section F, and within the chamber C, is the upper magazine-section F'. The lower section F of the magazine may incline backward, as shown in fig. 4, for the purpose of exposing a larger amount of incandescent fuel in front of it than behind it, and thereby throwing more heat toward the front of the stove than toward the back. The upper section of this magazine is preferably made crowning or hemispherical, so as to leave a free space all around and above it, except at the point where the feed-passage leads into it.

The feed-passage k is made in the form of an inclined chute, leading through the front convex portion of the top of section C, into the top of section F'.

This chute is formed by means of two vertical side-plates r r, and an inclined lip, r', which close the sides and bottom of the passage, but leave the upper side open and in communication with the space v, above the magazine-section F'.

The opening leading through the convexity of the section C is provided with a curved sliding door e, which moves in and is guided by grooves f, formed in the side-plates r r, as shown in figs. 4 and 6.

The grooves f are made in the arc of a circle, of such length as will allow the door e to be depressed far enough to expose the entire passage k, and also to allow the door to be moved upward and inward far enough to shut the opening leading into the passage or chute k, as well as that leading from this passage or chute into the space v, between the magazine-section F' and the outer casing C.

When the door e is shut, its upper edge abuts against a lip, l, formed on the magazine-section F, and a lip formed on the door receives a lip, s, which is formed on the upper edge of the top plate of section C, thus preventing leakage of gas.

The upper lipped edge of the opening through section C, considerably overhangs the corresponding edge of the opening into the magazine-section F, thereby bringing all the gas rising out of the magazine, under the influence of the draught, into the exit-pipe.

At the back of the top section C, outside thereof, a chamber, K, is constructed, which communicates, at its bottom, with the back horizontal extension B' of the combustion-chamber, through an opening provided with a valve, J.

Near the top of the chamber K is an opening, t, leading out of the top section C, and through the top of chamber K is an opening leading into the main flue-pipe H.

This pipe partly encroaches upon the top of section C, so that when the damper or valve J is shut, as shown in fig. 4, the products of combustion, after circulating through pipes S, base-flue c, columns E E, and the flue-space in section C, will escape freely from the latter into said pipe H.

D represents the upper portion of the frame, or fire-board, and indicates that portion of the stove which projects out into the room.

To this frame D, two sections, or segments G G, are permanently secured, which form, in combination with an intermediate segment, G', a perforated screen-cover for hiding from view the top of section C, and giving an ornamental appearance to the top of the stove.

The intermediate segment G' is secured to an arm, h, rising from the cover e, so that both of these covers move together in opening or closing the feed-passage leading into the magazine.

The slot c, made through the front of section C, allows the arm h to move down with the covers.

By thus connecting the cover e with the screen-section cover G', there is in fact but one movement to be made to open or to shut the feed-passage and gas-passage, which renders the operation very simple and convenient.

Operation.

When fire is first made on the grate, the rod j', extending from damper-rod j to the front of the stove, is moved, so as to raise the damper J from its passage, and allow a direct draught from the combustion-chamber through back extension B', through the flue-chamber K, and out through the main escape-flue H.

When the fire burns freely, and a direct draught is no longer required, the damper J is shut, as shown in figs. 2 and 4.

The direction of the products is then as follows:

They pass into the back extension B', and are equally distributed to the pipes S, down which they pass into the base-flue c'. Here the products are divided again, one-half passing to each one of the columns E, thence through these columns to and through the short pipes a, into the flue-chamber in section C.

Upon entering this section C, the products are directed a little forward by the two vertical wings i i, on opposite sides of the opening t. The products then pass back between said wings, and escape into the main flue H.

It will be seen from that part of the above description which relates to the top-feed magazine, that I prevent the escape of gas into the room, when the feed-door is removed from the feed-passage, by bringing the space above the coal in the magazine under the influence of the draught of the main flue of the stove, which draught will overcome any tendency of the gas rising into the room.

I also adopt a single plate, cover, or door, to shut the feed-passage, as well as the gas-passage, and thereby obviate an inconvenience which would attend the handing of two disconnected doors or covers.

I employ a chute, that is to say, a passage which is closed on three sides, for two purposes, namely, that the coal may be guided and directed into the fuel-magazine, and that lateral currents, which would be liable to direct gas into the room, shall not cross the feed-passage.

I also connect to the cover e, which closes both the feed-passage and gas-passage, the screen-section G, so that both of these parts move together.

This may be done, as shown in figs. 4, 6, and 7, by passing the arm h through a slot made through the section G', and using the cross-key g' above the bridge g. The arm h has shoulders formed on it, on which the section G rests and is held.

I do not limit my invention to making a part of the screen stationary, as I may have the whole screen attached to the curved plate e.

If desirable, the central portion G' may be simply a raised solid ornament cast on and with the cover e, such ornament being formed on the same curved line with the screen-sections G G, and the screen-sections G G being either stationary, as shown, or movable with the door or cover, in which latter case the screens will be castlike wings on each edge of the curved cover.

Having described my invention,

What I claim as new, and desire to secure by Letters Patent, is—

1. The gas-escape passage of the feed-chute fireplace magazine-stove, substantially as and for the purpose herein described.

2. The curved door e, substantially as and for the purpose described.

3. The arrangement of the door e, to open by a cir-

cular movement in the paths of a vertical plane, substantially as shown and described.

4. Making the chute-door *e*, a permanent part of the stove, and yet movable, substantially in the manner and for the purpose described.

5. The combination of the screen or screens and the attached, yet movable door *e*, substantially in the manner and for the purpose described.

6. The screen connected to the door *e*, so as to be readily disconnected therefrom, by means substantially as described.

7. The combination of the pipes *S*, combustion-chamber *B* *B'*, hollow flue-base *A*, return-columns *E*, and direct-draught damper, *J*, substantially in the manner and for the purpose described.

8. The combination of the damper *J*, feed-chute with gas-escape through it, the flue-chamber *K*, passage *t*, and main draught-flue, *H*, substantially in the manner and for the purpose described.

9. In a fire-place top-feed fuel-magazine stove, the combination of the following elements, to wit, the flue-extension *K*, the gas-escape *t*, direct damper *J*, the extension *B'*, and the pipes *S* *S*, substantially as and for the purpose described.

10. In a fire-place top-feed fuel-magazine stove, the combination of the following elements, to wit, an inclined chute, with a gas-passage leading therefrom into the main flue, a single cover or plate permanently attached to the stove, but movable so as to be made to close both the feed and gas-passages, or to open the same, and screen-sections *G* *G*, substantially as and for the purpose described.

JOHN J. MYERS.
